METHOD OF AND APPARATUS FOR MOLDING ARTICLES OF PAPER PULP

Harvey V. Mitchell, Bridgeport, Conn.

Application January 12, 1935, Serial No. 1,478

16 Claims. (Cl. 92—58)

This invention relates to a method of and apparatus for molding hollow articles of paper pulp. It has been the practice to mold such articles by filling a hollow foraminous mold with a dilute paper pulp stock and keeping the mold filled with stock until a sufficient wall thickness of pulp is accumulated against the inner surface of the mold, whereupon the supply of pulp stock is cut off and the residual liquid in the mold is 5 expelled by air or steam pressure which compacts and partially dries the pulp mat which has been deposited against the inner surface of the mold so that the article can be handled. The article is then removed from the mold and is 10 subjected to further drying and other treatment as desired. For commercial success in the manufacture of molded pulp articles, speed of production is a vitally important factor. In methods of molding pulp articles as now practiced, a very dilute pulp stock must be employed to get 15 satisfactory results. This means that a comparatively large volume of water must pass through the mold and the pulp mat deposited thereon in the course of molding an article. Consequently, the molding cycle must include a 20 time interval sufficient for the discharge of this water.

It is an object of the present invention to shorten the necessary time required for the molding of an article by diluting the pulp stock which enters the mold with air instead of extra water, so that the stock enters the mold mixed with air. In order to ensure a proper distribution of pulp fibers over the interior of the mold, the 25 pipe or nozzle through which the stock enters the mold may, according to the invention, be rotated and may also be axially reciprocated.

It is a further object of the invention to provide relatively simple and inexpensive apparatus 30 for molding pulp articles, and to make such apparatus capable of simple adjustments to adapt it for the requirements of articles of different sizes and shapes.

Various other novel and advantageous features 35 will be apparent to one skilled in the art from the disclosure of the invention in the description which follows, and in the drawings, of which

Figure 1 is an elevation, partly in section, of 40 apparatus embodying the invention.

Figure 14 is an elevation, partly in section, of 20 modified apparatus for controlling the pulp supply.

Figure 15 is a development of a portion of the 25 support table for the molds.

Generally speaking, the apparatus which is 30 illustrated as an embodiment of the invention comprises a supply tank 20 for the paper pulp stock of proper concentration. This tank may be supplied with an agitator (not shown) to

keep the stock well stirred according to usual 35 practice. Charges of pulp stock are drawn from the tank 20 through pipes 21 leading to control valves 22 into a pair of cylinders 25. While two cylinders 25 are shown, by way of illustration, for purposes of rapid production, it is evi-

dent that a single cylinder can be employed to 40 mold articles one at a time, or more than two can be provided for simultaneous operation.

When the cylinders have drawn in sufficient 45 charges of pulp stock, the valves 22 are operated as hereinafter explained to permit the discharge of the pulp through tubular nozzles 26 into hollow foraminous molds contained in casings 27.

The pulp is drawn into and discharged from the cylinders 25 by the reciprocation of pistons 50 connected to a piston rod 28 driven by suitable power mechanism such as a compressed air motor.

30 The pulp stock in passing from the cylinders 25 to the nozzles 26 passes through fittings 31 which contain mixing chambers in which the stock is mixed with air supplied through pipes 32 from a reservoir 35 and may also be mixed 55 with any other ingredient in liquid or powdery form such as coloring matter, sizing, coating material, or another variety of pulp stock, such other ingredient being supplied through pipes 36

from a supply tank 37. This tank is preferably 55

air tight so that compressed air may be supplied thereto as by a pipe 40, the material in the tank 37 being forced through a pipe 41 to the pipes 36 under pressure. The flow of air through the 5 pipes 32 may be controlled by a valve 42 operated by a cam 43. In like manner, a valve 44 may be operated by a cam 45 to control the flow of the ingredient supplied from the tank 37. It is not necessary to force material through the pipe 36 10 by compressed air as the flow of air from the pipe 32 ordinarily produces a suction at the orifice of the pipe 36, as hereinafter described. The nozzles 26, which enter the molds in the casings 27, are preferably rotated as by suitable 15 motors 50. For this purpose, suitable power means such as air-driven turbines may be employed, these turbines being connected by flexible connections 51 to the air manifold 35 through a control valve 52 which is operated by a cam 20 53. The speed of rotation of the turbine may be constant or varied during a molding cycle according to the shape of the cam 53. Air may be supplied to the manifold 35 from any suitable source of compressed air by means of a pipe 55. 25 The motor 30 may also be connected to a pipe 55 through a control valve 56 and a connecting pipe 57, the control valve being operated by a cam 60. The cams 43, 45, 53 and 60 may be driven by a constantly rotating shaft 61, which, 30 as shown, is connected by a gear 62 to a pinion 63 which is mounted on a shaft 64 driven through transmission mechanism 65 by any suitable source of power connected by a power belt 66. 35 The portion of the apparatus used for discharging the pulp stock into the mold is illustrated more particularly in Figures 2, 5 and 7. As shown, each cylinder 25 contains a piston 71 connected by a piston-rod 72 to a cross-head 13. 40 The piston rod 28 is secured to the cross-head 73 and to a power piston 75 in the motor 30 by reciprocation of the pistons 71. As the pistons 71 rise, they draw into the cylinders 25 charges of pulp stock from the supply tank 20. During 45 this portion of the cycle of operations, the pulp-control valves 22 are in the position shown in Figure 5. When the pistons 71 reach the upper end of their stroke, a finger 76 engages the upper of two adjustable lugs 77 and 78 on a control 50 rod 80, the lower end of which rod is connected to operating arms 81 of the valves 22. The rod 80 is thus shifted upwardly so as to rotate the valves 22 to the position shown in Figure 6. This shuts off the supply pipes 21 which lead from 55 the tank 20, and connects the cylinders 25 with the molding nozzles 26. The downward stroke of the pistons 71, which immediately follows, forces the pulp stock through the molding nozzles 26 until the pistons reach the bottom of 60 their stroke, at which point the rod 80 is shifted by engagement of the finger 76 with the lower lug 78, shifting the valves 22 to the position illustrated in Figure 5. During this flow of the stock through the nozzles 26, the nozzles are 65 vertically reciprocated as by connecting rods 82 which are attached to levers 83. These levers are rocked by crank arms 84 which are mounted on a shaft 85 and which engage the levers in slots 86. On the shaft 85 is a pinion 87 meshing with a rack 88 which is a part of or is secured to the piston rod 28. By selecting a pinion 87 of suitable size, the number of reciprocations of the nozzles 26 for each stroke of the pistons 71 can be determined. The length of 70 75 stroke of the nozzles 26 can be determined by

attaching the upper ends of the rods 82 at selected points on the levers 83, thus varying the effective length of the levers, or by replacing the crank arms 84 by crank arms of a different length. 5

As shown in Figure 5, the pulp stock which is discharged from each cylinder 25 through the corresponding valve 22 passes through a nozzle 90 which projects into a mixing chamber 91 in the corresponding fitting 31. The air pipe 10 32 opens into the chamber 91, so that, as the jet of pulp stock issues from the nozzle 90, it is surrounded by air flowing in the same direction. The mixture of air and pulp stock enters a pipe 92 which leads into the molding nozzle 15 26 as illustrated in Figure 7. With the mixture of pulp stock and air may be added another ingredient or ingredients supplied through one or more pipes 36, one such pipe being illustrated for each chamber 91. The rush of air past the 20 orifice of the pipe 36, with or without a stream of pulp stock flowing from the nozzle 90 past the orifice of the pipe 36, not only produces a suction effect in the pipe 36 but also violently breaks up the stream of such ingredient entering the chamber from the pipe 36 and thoroughly mixes it with the air stream and with the pulp stock if the latter is flowing. 25

The molding nozzle 26 may be a simple tubular member or may be supplied with a molding tip 95, 30 such, for example, as is illustrated in Figure 10. The molding tip shown in this figure is intended for the molding of relatively small articles or articles having a small opening which easily may be closed later to provide the finished article having a completely closed surface. During the flow of the pulp stock through each nozzle 26, the nozzle is preferably rotated by suitable apparatus such as a turbine 50 having a turbine wheel 100. The speed of rotation of the nozzle may be considerable, 4,000 to 10,000 R. P. M. being found suitable. The turbine wheel 100 may be closed in a suitable casing 101 to which is supplied a stream of air, steam, or other suitable fluid through a supply pipe 51 and a restricted passage 102 which 45 forms a high speed jet impinging on the blades of the turbine wheel 100, the power fluid being discharged as through outlet ports 103. Since it is usually desirable to reciprocate the nozzle 26 axially, the motor 50 is adapted to slide on the 50 pipe 92 with the nozzle 26, suitable packing being supplied as at 104 to prevent leakage from the casing 101 along the surface of the pipe 92. It is important that the nozzle 26 be freely rotatable on the pipe 92 and that the slight clearance between the surfaces of these nested members be kept clear. To this end, I may provide a small chamber 105 above the upper end of the nozzle 26 within the casing 101, this chamber acting as an air gland to provide constant pressure at the 60 upper end of the nozzle member 26. The pressure in the chamber 105 is supplied through a duct 106 leading directly from the compressed air supply pipe 51. A lower chamber 107 may also be supplied with compressed air through a 65 duct 108, the nozzle member 26 having a number of small holes 109 through which the air pressure in the chamber 107 may reach the clearance between the nozzle member 26 and the pipe 92. Thus this clearance is kept free from pulp fibers or any other foreign matter which might tend to clog the clearance and cause the nozzle member to bind. 70

The nozzle members 26 illustrated in Figure 2 are shown as directed vertically downward. In 75

molding articles of certain shapes, however, it may be desirable to introduce the stream of pulp stock at oblique angles or in an upward direction. To this end, the nozzle members 26 5 may be adjustable as indicated in Figures 3 and 4. Instead of being connected to its valve 22 by a straight pipe, each nozzle member may be connected to the valve 22 by a pipe having a horizontal portion 110 and a swivel joint 112. To 10 provide for the axial reciprocation of the nozzle member 26, a connecting rod having two parts 114 and 115 may be employed. The part 114 extends from the rocking lever 83 to a disk 116. The part 115 extends from the disk 116 to the 15 motor 50. As indicated in Figure 4, the disk 116 is provided with a series of holes 117 so that the rods 114 and 115 can be operably connected thereby for any angle of adjustment of the nozzle member 26.

20 The apparatus thus far described is capable of several simple adjustments. The amount of fiber for each molded article can be varied by altering the length of stroke of each piston 71 by modified operation of the motor 30. This 25 is easily done by changing the cam 60. This adjustment should be accompanied by suitable adjustment of the lugs 77 and 78 so that the valves 22 will operate at the end of each stroke. The speed of travel of the pistons 71 may also be 30 regulated at all points of their stroke by suitably shaping the control cam 60 to determine the extent as well as the duration of opening of the valve 56.

The cam 45 may be shaped as desired for the 35 operation of the valve 44 to control the time and rate of admission of an additional ingredient into the mixing chamber 91 to mix with the stock passing therethrough or to follow the introduction of stock into the mold. For example, a 40 filler, coloring or sizing can be injected into the pulp stream at any stage of its period of flow to modify all of the pulp entering the mold or only the outer or inner layer of pulp in the article formed in the mold. Or, if desired, the valve 45 may be opened just after the stream of pulp 45 stock is cut off, to coat the inner surface of the molded article. While only one unit for supplying auxiliary ingredients is illustrated, it is obvious that more can be employed.

50 The molds into which the nozzles 26 are introduced are of any desired shape according to the kind of article to be produced. A typical mold is illustrated in Figures 12 and 13, but it is understood that the invention is not limited to any 55 particular size or shape or details of structure of such mold. As shown, the mold unit consists of a cylindrical casing 27 within which is slidably inserted a circular series of radial vanes 120 supporting the foraminous mold elements 121 which constitute the mold itself. As shown, there 60 are two lateral elements 121 and 122 forming halves of the side wall of the mold. Cooperating with these members is a foraminous bottom piece 123 and a top piece 124. Attached to the top piece 124 is a suitable neck member 125 to guide the molding nozzle 26. The vanes 120 may be reinforced by semi-circular rings 130 so that the structure within the casing 27 comprises two principal members each including half of the mold 65 itself. The bottom member 123 may, if desired, be secured to one of these members or may be a separate part. These members are easily assembled with a top piece 124 and slipped into a casing 27, whereupon the mold unit is ready for 70 use.

In order to facilitate rapid production, a table or platform 140 may be provided as indicated in Figures 1 and 11. This table is adapted to rotate about the axis of the shaft 61. The table 140 is preferably driven with a step-by-step movement, suitable apparatus for this drive being illustrated in Figures 1 and 11. To this end, a pinion 141 is mounted on the shaft 64 and drives a gear wheel 142 which is mounted on a shaft 143. A disk 145 is also mounted on the shaft 10 to be driven thereby, this disk having a pin 146 which engages in successive slots 147 formed in a disk 150, the latter being secured to a sleeve 151 which is a part of or is secured to the table 140 so that the table is driven with the disk 150. 15 As is evident from Figure 11, the engagement of the pin 146 in successive slots 147 during the rotation of the disk 145 results in rapid indexing movements of the table 140 alternating with considerably longer periods of dwell. Thus each 20 mold unit 27 is held beneath a molding nozzle 26 for a sufficient period for the molding operation, and then is shifted along to be replaced by a fresh mold unit 27.

It is desirable, according to the invention, that 25 the molds 27 be rotated during the molding operation and also after the molding operation, so that the water in the pulp stock will be more thoroughly drained by centrifugal force from pulp deposited within the mold in the form of the 30 article which is molded. To this end, the table 140 is provided with a number of individual platforms 160, each of which is individually rotatable on a vertical axis, being mounted on a vertical spindle 161 for this purpose. Each spindle 161 35 with its platform 160 is vertically movable and is pressed downwardly both by the weight of the platform 160 with the mold 27 thereon and also by a spring 162 if desired. For the rotation of the spindles 161 with the platform 160, a pair of 40 friction disks 165 and 166 may be mounted on each spindle 161, these disks being adapted for selective frictional engagement with a central driving disk 170. The driving disk may be constantly rotated by any suitable means. As shown, 45 a gear wheel 171 is mounted coaxially therewith and meshes with a pinion 172 mounted on the constantly driven shaft 143. It is evident from Figure 1 that the molds will be rotated unless the spindle is elevated to an intermediate position wherein neither the friction disks 165 or 166 is in engagement with the driving disk 170. The speed of rotation of the molds may vary 50 widely according to the size and shape of the article to be molded, but ordinarily will not exceed 55 500 to 600 R. P. M. The direction of rotation may be with or opposite to the direction of rotation of the nozzle 26, as desired, the geared connections with the motor 65 being arranged accordingly. In some cases it may not be practical to rotate the molds at all. When the molds are rotated, it is desirable that they be rotated continuously while on the platform 160 except when at the loading station where molds having 60 molded articles therein are removed from the table 140 and are replaced by fresh molds ready to receive the molding nozzle 26. To this end, the platforms 160 may be partially elevated at the loading station as by a stationary cam member 175, indicated in Figure 15, so that at this 65 stage of the travel of each platform 160 its rotation is temporarily stopped so as to facilitate the exchange of the mold 27 thereon for a fresh mold. With the next indexing movement of the table 140, the platforms 160 at the loading station move 70 75

into the molding station. At this station it is desirable to elevate the platforms still further so as to move the necks 125 of the molds to telescope over the lower ends of the nozzles 26. 5 Thus, when the nozzle 26 begins its downward reciprocating motion, its lower end is already within the interior of the mold. For such further elevation of the platforms 160, I may provide an actuating lever 180 pivoted as at 181 and 10 rocked as by a cam 182. As shown in Figure 1, this cam may be in the form of a disk mounted on the shaft 61 to be driven thereby. The shaft 61 is timed so that it makes a single rotation for every complete molding cycle. The lever 180 is 15 adapted to engage the lower ends of the spindles 161 which are directly beneath the molding nozzles 26.

A modified form of drive for the pulp stock piston 71 is illustrated in Figure 14. Instead 20 of a fluid motor for driving this piston, a crank wheel 185 may be employed, this being connected as by a pitman 186 the upper end of which is radially adjustable on the wheel 185 so as to vary the stroke of the piston 71. The crank 25 wheel 185 may be driven through bevel gears 187, a connecting shaft 188, a second pair of gears 189 and a shaft 190, the latter being operably connected to the shaft 61 through clutch mechanism such as is indicated in Figure 14. As 30 shown, the shaft 61 drives a clutch member 191 which is adapted to mesh with a corresponding clutch member 192 fixed on the shaft 190. The clutch member 191 is moved into and out of engagement with the member 192 as by a 35 sliding member 193 having a cam follower 194 riding on a cam 195 which is secured to the shaft 61. As the cam 195 rotates with the shaft 61, the cam follower 194 rides into and out of a depression 196, disconnecting the clutch members 191 and 192 so that the movement of the 40 pistons 71 is stopped until the cam follower 194 rides out of the depression 196 and throws in the clutch against the pressure of a spring 197.

The operation of the mechanism hereinbefore 45 described through the molding cycle is as follows. Starting the cycle at the moment when the table 144 has been indexed so as to bring fresh molds 27 into position for the molding operation, the arm 180 is rocked by the cam 182 50 so as to elevate the platforms 160 which are beneath the molding nozzles 26. This elevation is sufficient to project the lower ends of the nozzles 26 into the interior of the molds. During the indexing movement of the table 140, the pistons 55 71 are arrested at a point near to the upper end of their stroke, the valves 22 being at such time in the position shown in Figure 5. The moment the molds 27 are elevated into position telescoping the lower ends of the nozzles 26, the 60 cam 60 actuates the control valve 56 so as to cause the motor 30 to complete the upward stroke of the pistons 71. This movement results in shifting of the valves 22 to the position shown in Figure 6. The motor 30 is at once reversed 65 by the cam 60 to force the pistons 71 downward, thus sending a stream of pulp stock down through the mixing chambers 91 and the rotating nozzles 26. Simultaneously with or slightly prior to the actuation of the motor 30, the air valve 70 42 is opened by the cam 43 so that a stream of air is sent to each of the mixing chambers 91, so that, when the streams of the pulp stock from the cylinders 25 reach the mixing chambers, the air is already flowing through the chambers 75 to mix therewith. At present it is not entirely

understood just what form the mixture of air and pulp stock takes in the tube 92 and the nozzle 26. The mixture is probably in the form of a foam which travels downwardly at considerable speed and enters the interior of the mold. Some 5 of this foam is caught by the whirling nozzle 26 and is given centrifugal movement so that the pulp flies tangentially from the lower end of the nozzle. During the flow of pulp stock into the mold, the nozzle may be axially reciprocated 10 to assist in the even distribution of the pulp on the interior surface of the foraminous mold. The air pressure and the centrifugal velocity of the pulp discharged from the nozzle tend to compact the mat which is built up against the 15 inner surface of the mold so that the resulting molded article is well compacted and has a smooth inner surface.

When the pistons 71 reach the lower extremity 20 of their stroke, the valve 22 is shifted from the position shown in Figure 6 to the position shown in Figure 5, so that, as the pistons move upwardly, the cylinders 25 are again charged with pulp stock from the tank 20. Meanwhile the air continues to flow through the nozzles 26, compacting the pulp mat against the interior surface of the mold, thus driving out more and more of the white water from the pulp. This extraction of water from the pulp is assisted by the 25 rotary movement of the molds themselves, due to the engagement of the disks 166 with the driving disk 170. When the pistons 71 have reached their position of dwell near the upper limit of their stroke, the cam 60 operates to stop the motor 30 and the cam 43 operates to shut off the flow of compressed air into the molds. The reciprocating mechanism for the nozzles 26 is so arranged that, when the pistons 71 reach this position of dwell, the nozzles 26 are in their extreme uppermost position. The cam 182 30 operates at this point to rock the lever 180 so as to lower the molds 27 clear of the nozzles 26. This brings the disks 165 instead of the disks 166 into contact with the driving disk 170 so that the rotation of the molds is uninterrupted. The table 35 140 is now indexed to move the molds with freshly molded articles away from the nozzles 26 and to move empty molds into the molding position. The molds thus continue to rotate about their own axes throughout their step-by-step journey 40 around the table 140 until they again reach the loading position, whereupon their rotation stops 45 so that they can be removed from their platforms 160 and be replaced by fresh molds.

It is evident that various modifications and 50 changes may be made in the methods and apparatus herein described without departing from the spirit or scope of the invention as defined in the following claims.

I claim:—

1. A method of molding articles of paper pulp, which comprises mixing air and pulp stock, passing the mixture through a nozzle into a hollow foraminous mold, and rotating the nozzle on its 65 axis while the mixture is passing therethrough.

2. A method of molding articles of paper pulp, which comprises mixing air and pulp stock, blowing the mixture through a nozzle into a hollow foraminous mold, and rotating and axially reciprocating said nozzle while the mixture is passing 70 therethrough.

3. A method of molding articles of paper pulp, which comprises mixing air and pulp stock, blowing the mixture into a hollow foraminous mold, 75

and rotating said mold while said mixture is entering thereinto.

4. A method of molding articles of paper pulp, which comprises mixing air and pulp stock, blowing the mixture through a nozzle into a foraminous mold, and rotating both said nozzle and mold during the flow of said mixture.

5. A method of molding articles of paper pulp, which comprises mixing air and pulp stock, blowing the mixture through a nozzle into a hollow foraminous mold, and axially reciprocating said nozzle during the flow of stock therethrough.

6. Apparatus of the class described, comprising a nozzle adapted to project into a hollow mold, means for rotating said nozzle about its axis, a mixing chamber communicating with said nozzle, a supply pipe for pulp stock projecting into said chamber, and means for supplying air under pressure into the space in the chamber around the end portion of said supply pipe.

7. Apparatus of the class described, comprising a tank for pulp stock, a pump cylinder, a piston reciprocable in said cylinder, a connecting pipe from said tank to said cylinder, a control valve in said pipe, a discharge pipe leading from said valve, said valve being operable to connect said pump cylinder alternately with said tank and said discharge pipe, a foraminous mold having a charging opening, a rotatable molding nozzle communicating with said discharge pipe, said nozzle being separable from said mold and insertable into said mold through said opening to close said opening during charging of said mold, and automatic means for operating said valve at the end of each suction stroke of said piston to connect the pump cylinder with said discharge pipe and at the end of each expulsion stroke to connect the pump cylinder with the tank.

8. In molding apparatus for paper pulp, a mixing chamber, a pulp stock supply pipe having an end portion and terminal orifice within said chamber, a discharge pipe leading from said chamber directly opposite said orifice, means for introducing air under pressure into the space in said chamber surrounding said end portion of the supply pipe, and means for injecting another fluid into said chamber.

9. A method of molding articles of paper pulp, which comprises mixing air and pulp stock, blowing the mixture through a nozzle into a hollow foraminous mold, and causing relative movement between said nozzle and mold during the flow of air and pulp stock mixture whereby to control the distribution of stock over the interior surface of the mold.

10. Apparatus of the class described, comprising a rotatable molding nozzle, means for periodically passing pulp stock through said nozzle, means for axially reciprocating said nozzle during the passage of stock therethrough, means for introducing air through said nozzle, a hollow mold having a top orifice adapted to receive and guide said nozzle, conveyor means for moving said mold into and out of molding position beneath said nozzle, means for elevating said mold into telescoped relation with said nozzle after moving into said molding position and for lower-

ing the mold clear of the nozzle before moving from said molding position and means for rotating said mold while in its elevated position.

11. A method of forming hollow articles of fibrous material which comprises causing a liquid suspension of said fibrous material mixed with a gaseous diluent to flow in a predetermined direction with a whirling movement, and projecting said whirling mixture from a restricted opening against the surface of a hollow foraminous mold whereby said fibrous material is restrained on said surface and said liquid and diluent is freed from said fibrous material.

12. A method of forming hollow articles of fibrous material in a foraminous mold which comprises causing a stream of liquid suspension of fibres to flow in a direction substantially parallel with the axis of the mold under a higher pressure than normal gravimetric pressure while simultaneously causing said fibres to whirl in a generally circumferential direction about the axis of said stream whereby to impart energy to said fibres tending to cause them to flow in a direction toward the inner surface of the walls of said foraminous mold and then causing said fibres to flow against said surface with sufficient impact to build a wall of fibrous material thereon and free the major portion of said liquid from said fibres and introducing into the current of the fibrous material a gaseous medium moving in the same general path as said fibrous material.

13. A method of molding hollow articles of paper pulp, which comprises flowing pulp stock through a nozzle into a hollow foraminous mold, rotating the nozzle whereby to throw the pulp and form a wall, and introducing into said flowing pulp stock a substance in gaseous phase and in sufficient quantity to build up a pressure within said mold sufficiently greater than atmospheric, whereby to assist in depositing and compacting said pulp wall.

14. A method of molding hollow articles of paper pulp, which comprises flowing pulp stock through a rotating nozzle into a substantially closed hollow foraminous mold, and supplementing the flow of pulp stock with a flow of gas in sufficient quantity to produce a substantial differential pressure between the interior and exterior of said foraminous mold whereby to assist in compacting and drying the paper pulp.

15. A method of molding articles of paper pulp, which comprises mixing a gaseous medium and pulp stock, passing the mixture through a nozzle into a foraminous mold, rotating the nozzle on its axis while the mixture is passing therethrough, whereby to throw the pulp and form a fibrous wall and introducing into said mold a different material in liquid or suspended form to be retained on said fibrous wall.

16. Apparatus of the class described, comprising a nozzle adapted to project upwardly into a foraminous mold, means for rotating said nozzle about its axis, a supply pipe for pulp stock connected with said nozzle and means for supplying air under pressure through said nozzle into said hollow mold.
